The ornamental design for a water bottle, as shown and described.

DESCRIPTION

FIG. 1 is a perspective view of the water bottle embodying the new design;

FIG. 2 is a front view thereof;

FIG. 3 is a rear view thereof;

FIG. 4 is a right-side view thereof; the left-side view being a mirror image thereof;

FIG. 5 is a top view thereof; and,

FIG. 6 is a bottom view thereof.

The broken lines show portions of the water bottle that form no part of the claimed design.
